UNITED STATES PATENT OFFICE.

WILLIAM W. ALLEN, OF CINCINNATI, OHIO.

SWITCH-STAND.

No. 895,395.

Specification of Letters Patent.

Patented Aug. 4, 1908.

Application filed October 7, 1907. Serial No. 396,140.

To all whom it may concern:

Be it known that I, WILLIAM W. ALLEN, a citizen of the United States, residing at Cincinnati, in the county of Hamilton and State 5 of Ohio, have invented certain new and useful Improvements in Switch-Stands, of which the following is a specification.

My invention relates to that class of switch stands in which the throwing lever lies parallel to the track, necessitating the use of a gear and segment to transmit the motion to throw the switch, the object being to efficiently operatively connect the segment with the switch in such a manner as to allow the 15 operating mechanism of the switch stand to be inclosed and fully protected from the weather.

My invention consists in a segment rotatably mounted in a stand, a gear adapted to 20 rotate with the throwing lever and to transmit the motion of the throwing lever directly to the segment, slots in the bottom of the base, and studs on the segment extending downward through the slots, these studs being adapted to be connected with the switch 25 by means of a suitable connecting bar.

My invention also consists in the parts and in the details of construction and arrangements of parts, as will hereinafter be more 30 fully described and claimed.

In the drawing: Figure 1 is a side elevation, and Fig. 2 is a plan view of a switch stand embodying my invention. Fig. 3 is a cross section on the line $x-x$ of Fig. 2. Fig. 35 4 is a detail perspective view of the segment and its studs. Fig. 5 is a section on the line $y-y$ of Fig. 4.

As I prefer to embody my invention, the base of the switch stand comprises the lower 40 casing 1, to which is secured the upper casing 2 by means of suitable bolts 3 and 4, the bolts 3 having their heads inclosed in recesses 5 in the side members 6 of the lower casing 1, so that the side members 6 may be 45 secured to the sleepers 7 by means of spikes engaging within the recesses 8, as is usual in the construction of this class of switch stands. The bolts 4 take through lips 9 on the upper and lower casing, and these lips 9 also serve 50 as bearings for the horizontal shaft 10 which extends within and without the base with its center on the line of contact of the upper and lower casings. Centrally of the base, a vertical shaft 11 is journaled in the top of the 55 upper casing and in the bottom of the lower casing, and, adjacent to the bearing of the

vertical shaft 11, a bearing lug 12 is provided on the under side of the top of the upper casing, extending downward to form an additional journal bearing for the longitudinal 60 shaft 10, the shaft 10 being reduced where it is journaled in this lug 12 to form a shoulder bearing against the lug to limit lengthwise movement of the shaft in one direction. The bevel gear 13 is mounted on this shaft 65 between the inner side of the base and the lug 12, being rigidly secured to the shaft by means of a pin 14 passing diametrically through its hub 15 and through the shaft 10. This gear 13 is also provided with a hub 16 70 on the side opposite to the hub 15, to bear against the inner side of the base and limit lengthwise movement of the shaft 10 in the other direction. Outside of the base, the throwing lever 17 is rigidly mounted on the 75 shaft 10 by means of a key 18, and pin 18*.

Mounted on the vertical shaft 11 and supporting this vertical shaft by means of a pin 19, is the segment 20 which bears on the upper side of the bottom of the base with its 80 hub 21. This segment is provided with gear teeth 22 by means of which the gear 13 may mesh with it, and also forms a double-throw crank by means of its yoke, which yoke is provided with studs 24 and 25 located diametrically opposite with respect to the center of the vertical shaft 11. This double-throw crank is provided, as is usual in the construction of switch stands, in order to adapt the switch stand for use on either side 85 of the track. These studs 24 and 25 are rigidly secured in the yoke 23 by means of their rivet heads 26 and 27, respectively, and extend downward from the lower side of the yoke through slots 28 and 29, respectively, 95 in the bottom of the base. These slots conform to the arc of reciprocation of the studs 24 and 25, and, as shown in the drawing, are made of somewhat greater width than is necessary to give clearance to the studs in order 100 to adapt them for use with cranks of different radii, which are used with switches having different ranges of movement in their operation. However, the width of these slots may be only sufficient to give the proper 105 clearance to the studs, and it is desirable to limit the size of these slots in order that the opening in the base may be as small as possible.

Below the lower side of the bottom of the 110 base, the studs 24 and 25 are reduced to form wrists 30 and 31, respectively, upon which

- may be secured a suitable connecting rod 32 by means of a strap 33 and bolts 34. As will be understood, this connecting rod will be attached to either of the studs as the case 5 may require. Thus a single-throw crank with one stud and one slot is sufficient for the operation of the switch stand, the other stud and slot being provided for optional use only.
- 10 Switch stands have been constructed in which the connecting rod is attached directly to the segment with which the gear meshes, and in which the connecting rod extends through an opening in the side of the 15 base toward the track, this opening being of sufficient size to allow the connecting rod to swing in its operative movement as actuated by the segment. Such an opening in the side of the switch stand forms a means of entrance for water and snow which may collect 20 in sufficient quantity, and, under certain conditions of the weather, freeze sufficiently hard to effectually prevent the operation of the switch, or to allow only partial operation 25 of the switch with the consequence of breaking some of the operating parts. In some instances, this collection of water and snow may, by freezing, burst the base or casing of the switch stand.
- 30 In order to obviate the above inconveniences, switch stands have been constructed with the sides completely closed and provided with a vertical shaft upon which is rigidly mounted the segment inside and 35 closed in the base, with a separate crank rigidly mounted on the vertical shaft below and outside the base, to which crank is attached the connecting rod. In such a construction, the bottom, as well as the sides of the base 40 may be completely closed. However, this construction has proved unsatisfactory owing to the fact that the entire strain incidental to the operation of the switch, must be transmitted from the segment within the 45 base to the vertical shaft, and from the vertical shaft to the crank outside the base. Such a construction requires extremely secure attachment of the segment and crank to the vertical shaft, it being found in practice 50 that the pins passing through the segment and shaft, and through the crank and shaft, are sheared apart in use, leaving the switch inoperative. As a better means of securing the segment or crank, or both, to the vertical 55 shaft, the vertical shaft has been forged square and square holes provided in the segment and crank. The production of a switch stand of such a construction proves impracticable owing to the necessity of obtaining 60 a very accurate fit between the square forged part of the vertical shaft and the square holes in the segment and crank, in order to obviate lost motion of these parts. Such a construction, when made sufficiently 65 accurate, is disproportionately expensive.

Also, although a switch stand may be constructed as above, without openings, either in the top, sides or bottom, for the passage of the operating parts, except the openings for the journal bearings of the shafts, it has been found that water will enter the switch stand through the last mentioned openings, and if there be no outlet in the bottom of the base, the water will collect inside the base, and may freeze, with the results above mentioned. It will therefore be seen that it is desirable to have the connecting rod attached directly to the segment without the use of the vertical shaft to transmit the force required to operate the switch, so that this vertical shaft may be relieved of the strain incidental thereto and allowed to act merely as the pivot for the segment. It is also desirable to provide a drain opening of limited size in the bottom of the base. By utilizing such a drain opening to permit a stud on the segment to extend below the bottom of the base for operative connection to the switch by means of the connecting rod, the relieving of the strain on the vertical shaft is accomplished, allowing the connection between the segment and the vertical shaft to be comparatively light, since its only duty is to cause the rotation of the vertical shaft to operate the target 35. 95

The radius of the gear on the horizontal shaft being less than that of the segment, the difficulty due to the shearing of the pin 14 will not be encountered owing to the greater mechanical advantage present in the operation of the horizontal shaft, than would be present in the operation of the vertical shaft in the same manner. The greatest difficulty heretofore encountered in the use of the horizontal shaft consists in its unsteadiness due to the fact that it has only been provided heretofore with the single journal bearing where it extends outside the base, and which difficulty I obviate by providing the additional journal bearing 12 within the base to receive and support the inner end of the horizontal shaft 10. In the construction here described, it will be noted that the relative size and location of the slots 28 and 29 in the base allow a substantial rib 36 to be formed, carrying the lower journal bearing of the vertical shaft, this rib extending in a direction perpendicular to the track, which is the direction of greatest strain on this part of the switch stand in operation. This rib, as well as the other parts of the base adjacent to the slots, is left smooth in order to facilitate the drainage of the base. 115 120 125

Having fully described my invention, what I claim as new and desire to secure by Letters Patent is:

1. In a switch stand, a crank mounted to reciprocate on a horizontal plane, means for reciprocating said crank, a stud on said crank by which it is adapted to be operatively con- 130

nected to a switch, a base forming a support and casing for said crank and its operating means, and a slot in the bottom of said base through which the stud extends to operatively connect with the switch, substantially as and for the purposes specified.

2. In a switch stand, a base, a segment mounted in said base and adapted to reciprocate in a horizontal plane, a gear journaled at right angles to the plane of reciprocation of said segment and in mesh with said segment, means for reciprocating said gear, a stud extending downward from said segment and a slot in the bottom of said base through which said stud extends to operatively connect with the switch.

3. In a switch stand, a base, a crank, a stud on said crank, a slot in the bottom of said base through which said stud extends to operatively connect with the switch, means for rotating said crank, a target shaft, and a connection between said crank and said target shaft whereby it is adapted to rotate with said crank, and whereby the connection between said crank and said target shaft is relieved of the strain incidental to the operation of the switch, substantially as and for the purposes specified.

4. In a switch stand, a base, a segment mounted in said base and adapted to reciprocate in a horizontal plane, a vertical target shaft, a connection between said segment and said target shaft, a gear journaled at right angles to the plane of reciprocation of said segment and in mesh with said segment, means for reciprocating said gear, a stud extending downward from said segment, and a slot in the bottom of said base through which said stud extends, to operatively connect with the switch whereby the connection between said segment and said target shaft is relieved of the strain incidental to the operation of the switch, and whereby the opening for operatively connecting the segment to

the switch is confined to the bottom of said base, substantially as and for the purposes specified.

5. In a switch stand, a base forming a casting, a vertical shaft, a segment pivoted on said vertical shaft to reciprocate in a horizontal plane, a horizontal shaft extending without the casing formed by said base and having a journal bearing therein, an additional journal bearing for said horizontal shaft within said casing adjacent to said vertical shaft, a gear on said horizontal shaft in mesh with said segment, a stud on said segment extending downward therefrom, a slot in said base through which said stud extends to operatively connect with the switch, a connection between said segment and said vertical shaft whereby they may reciprocate together, a connection between said gear and said horizontal shaft, whereby said gear may be rotated to reciprocate said segment, the connection between said gear and said horizontal shaft being adapted to transmit the strain incidental to the operation of said switch, and the connection between said segment and said vertical shaft being relieved of said strain, substantially as and for the purposes specified.

6. In a switch stand, a base, switch operating mechanism mounted in and inclosed by said base, slots in the bottom of said base adapted to allow the extension of part of said operating mechanism outside the base, and operative connection with the switch, said slots being adapted to form drain openings in said base, and being so proportioned and arranged relative to each other that a rib is formed in the bottom of said base extending in the line of direction of the greatest strain on said base in the operation of said switch.
